(57) **CLAIM**

The ornamental design for an electric stapler, as shown and described.

DESCRIPTION

FIG. 1 is a perspective view of the front, left and top of an electric stapler showing my new design;

FIG. 2 is a top plan view thereof;

FIG. 3 is a front view thereof;

FIG. 4 is a right side view thereof;

FIG. 5 is a left side view thereof;

FIG. 6 is a bottom view thereof; and,

FIG. 7 is a perspective view of the usage thereof.

The elements shown in broken lines are for illustrative purposes only and form no part of the claimed design.
